UNITED STATES PATENT OFFICE.

ANNA PISTORIUS, OF CHICAGO, ILLINOIS, ASSIGNOR TO THEODORE A. SCHMIDT LITHOGRAPHING COMPANY, OF CHICAGO, ILLINOIS, A CORPORATION OF ILLINOIS.

DESIGN FOR A BOX COVER PAPER.

Application filed February 14, 1927. Serial No. 20,763 Term of patent 7 years.

To all whom it may concern:

Be it known that I, ANNA PISTORIUS, a citizen of the United States, residing at Chicago, in the county of Cook and State of Illinois, have invented a new, original, and ornamental Design for Box Cover Paper, of which the following is a specification, reference being had to the accompanying drawing, forming part thereof.

The figure is a plan view of a sheet of box cover paper showing my new design.

I claim:

The ornamental design for a box cover paper as shown.

In witness whereof, I hereunto subscribe my name, this 2nd day of February, 1927.

ANNA PISTORIUS.
